TOY

Joseph Klarke, Mishawaka, Ind., assignor to
South Bend Toy Mfg. Co., South Bend, Ind.

Application April 26, 1937, Serial No. 138,945

4 Claims. (Cl. 273—118)

This invention relates to improvements in toys, and has for its primary object to provide a novel toy construction adapted to utilize a field of static electricity as means for actuating a movable part.

5 A further object is to provide a toy having a freely movable part energized in an erratic manner indeterminable in advance by an electrical field.

10 A further object is to provide a toy having a surface adapted for creation of a field of static electricity by friction, and associated means for retaining a member energized by said field within the influence of said field.

15 A further object is to provide a novel toy which is simple in construction and operation.

In the drawing:

Fig. 1 is a perspective view of the toy.

Fig. 2 is a top plan view of the toy when positioned at right angles to the position in Fig. 1.

20 Fig. 3 is an end view of a modified embodiment of the toy.

Fig. 4 is a longitudinal sectional view taken on line 4—4 of Fig. 3.

Fig. 5 is a perspective view of a part of the toy.

25 Referring to the drawing, which illustrates one embodiment of the invention, the numeral 10 designates a frame formed of any suitable material, such as sheet metal, to provide a base portion 11 and parallel side walls 12 extending perpendicularly from said base portion. Frame 10 has connected thereto a pair of cylindrical members 13 provided with longitudinally extending

30 radial grooves 14 into which the ends of base portion 11 of frame 10 fit. A sheet 15 of rubber is positioned between side walls 12, and is stretched between cylinders 13 and passed therearound for insertion of its end portions 16 into grooves 14. The walls 12 are of a height to project above the sheet 15 a substantial distance, and base portion 11 is of slightly greater width than the length of cylinders 13. Grooves 14 are of a width to tightly receive and retain the ends of the rubber sheet 15 and base portion 11 and thereby frictionally connect the parts in operative 35 relation.

40 A pith ball 17 forms a freely movable part associated with the toy. Thus, by rubbing the sheet 15 several times, as by the hand and particularly by the back of the finger nails, a field of static electricity is created. By applying the pith ball 17 to the toy after this field has been created, the ball is caused to move in a very erratic movement as long as the strength of the field subsists. The toy may be positioned for support by cylinders 13 45 with sheet 15 horizontal, as illustrated in Fig. 2;

or may be supported by one of the sides 12 with sheet 15 vertically positioned, as illustrated in Fig. 1. The electrical field serves to energize and shift the ball 17 in either of these positions. Thus, when positioned with sheet 15 horizontal, 5 the ball 17 will move horizontally on the sheet in an erratic and unpredictable manner having both lateral and longitudinal components. When the device is positioned with sheet 15 vertical, the ball is caused to move under the influence of the 10 electrical field in a substantially "bouncing" vertical manner with varying components of longitudinal movement.

While the greatest need for retention of the ball as it moves under the influence of the electrical field is met by the side walls 12, it may be desirable to provide retaining means at the ends of the device to prevent the ball from longitudinal movement to a point beyond the sphere or area of the electrical field of the device. For this 20 purpose, as illustrated in Figs. 3 and 4, end walls may be provided, formed by narrow flanges 18 projecting from the ends of side walls 12 and bent to transverse relation to sheet 15. It is desirable that these flanges 18 extend adjacent 25 the sheet 15 and be sufficiently narrow to minimize interference with the frictional rubbing of said sheet, the height of said sheet being preferably just sufficient to prevent ball 17 from moving longitudinally away from the device and the 30 electrical field.

If desired, suitable score indicating means may be provided on the device. Thus, in Fig. 1, I have illustrated an arrangement wherein one of the side walls 12 is provided with a plurality of transverse linear marks 19 defining areas on its inner face whose scoring value is designated by indicia 20. In other words, when the device is positioned with the sheet 15 vertical and the ball is applied and subjected to the influence of the electrical 35 field, the ball will move as above defined until the strength of the field weakens to an extent which is insufficient to further energize the ball, and the score for that operation is determined by the particular indicia 20 in the area at which the ball 40 comes to rest. A second scoring arrangement is illustrated in Fig. 2 for use when the device is positioned with sheet 15 horizontal. Thus, certain areas of sheet 15 are outlined by lines or marks 21, and indicia 22 designate the scoring 45 value of a play when the ball 17 comes to rest within the area defined by a mark 21.

It is well known that there are various substances which can be rubbed to produce static electricity. It will be obvious, therefore, that my 50 55

toy is susceptible of modification to utilize such substances for that purpose in place of the rubber sheet here described and illustrated.

I claim:—

- 5 1. A toy comprising a pair of supports, a substantially U-shaped frame carried by said supports, a member tensioned between said supports and positioned between the sides of said frame, and having an electrical field, and an object influenced by said field for free movement on said member and retained by said frame, said member holding said supports in operative relation to said frame.
- 10 2. A toy comprising a frame having opposed walls, a flexible member between said walls adapted to be rubbed to create static electricity, a support for each end of said frame, said support
- 15

mounting said flexible member, a member freely movable under the influence of said static electricity, at least one of said walls bearing scoring indicia.

3. A toy comprising a rigid U-shaped frame, a pair of spaced supports, and a rubber sheet positioned between intermediate portions of opposed sides of said frame, said frame and sheet extending between said supports.

4. A toy comprising a U-shaped frame, a pair of grooved supports, and a rubber sheet, the ends of said frame and said sheet being inserted in said grooves, said sheet extending around said supports and therebetween to hold said supports in operative relation to the ends of said frame. 15
